UNITED STATES PATENT OFFICE.

ALBERT J. BARBER, OF STEUBENVILLE, OHIO, ASSIGNOR TO THE PIPE MACHINERY COMPANY, OF CLEVELAND, OHIO, A CORPORATION OF OHIO.

ATTACHMENT FOR TAPPING MACHINES.

1,426,273.

Specification of Letters Patent. Patented Aug. 15, 1922.

Application filed May 17, 1920. Serial No. 381,927.

To all whom it may concern:

Be it known that I, ALBERT J. BARBER, a citizen of the United States, resident of Steubenville, county of Jefferson, and State 5 of Ohio, have invented new and useful Improvements in Attachments for Tapping Machines, of which the following is a specification, the principle of the invention being herein explained and the best mode in which 10 I have contemplated applying that principle, so as to distinguish it from other inventions.

My invention relates to tapping machines, drilling machines, lathes and the like, and 15 particularly to attachments for holding pipe couplings while the same are being threaded. The invention particularly relates to mechanism of this character by means of which the yoke and gripper jaws can be flipped or 20 turned over while supported in the pan or table so as to present the bottom end of the coupling to the tap, after the top end thereof has been properly threaded. Other improvements in apparatus of this character 25 contemplated by the invention will appear in detail in the accompanying drawings and be hereinafter specifically described and claimed.

The annexed drawings and the following 30 description set forth in detail certain means embodying my invention, the disclosed means, however, constituting but one of the various mechanical forms in which the principle of the invention may be applied.

35 In said annexed drawings:

Figure 1 represents a front elevation of one unit of a machine to which a pair of my improved attachments have been applied, showing a single pan and a pair of spindles;

40 Figure 2 represents a fragmentary plan view of the invention, upon an enlarged scale, and taken in the plane indicated by the line II—II, Figure 1, showing the attachment ready for turning to present the bottom end of the coupling to the tap;

45 Figure 3 represents a view similar to that of Figure 2, but showing the attachment in position for tapping;

Figure 4 represents a fragmentary front 50 elevation, upon the scale used in Figure 2;

Figure 5 represents a longitudinal vertical section taken in the plane indicated by the line V—V, Figure 3;

Figure 6 represents a vertical transverse 55 section taken in the plane indicated by the line VI—VI, Figure 3;

Figure 7 represents a vertical transverse section taken in the plane indicated by the line VII—VII, Figure 2;

Figure 8 represents a view similar to 60 Figure 7, but showing the coupling, yoke and gripping blocks being turned; and

Figure 9 represents a vertical longitudinal section taken in the plane indicated by the line IX—IX, Figure 2.

Referring to the annexed drawings, there is indicated by the ordinal 1, a single pan or table of one unit of a tapping machine, the same forming a support for my improved attachment. Upon this table 1 is mounted a yoke 2 having a series of spaced outwardly extending tooth-like members 4 upon each side, adapted to register with a series of similar inwardly extending members 3 formed upon the table 1. In a manner hereinafter fully described, the yoke 2 may be moved longitudinally of the table 1 so as to cause the members 3 and 4 either to lie one above the other, whereby the yoke 80 70 75 80 85 90 95 2 can rest upon the table 1, or to be relatively staggered, so as to enable the teeth 4 to pass the teeth 3, during a flipping or turning over of the yoke 2, effected in a manner hereinafter fully described. The yoke 2 is a support for gripper blocks 5 and 6 adapted to receive and clamp between them the work 18 during the tapping operation. Steel pieces 7 and 8 are inset in the blocks 5 and 6, and against them coupling 18 is clamped. The aforementioned turning of the yoke 2, blocks 5 and 6, and coupling 18 is effected upon two supporting trunnions 9 and 10. The former of these trunnions is projected forwardly from the rear of the table 1 through a supporting bearing 1' and tapped into the yoke 2, and the latter is projected rearwardly of and

through the table 1, supported within a front bearing 1', and secured within the gripper block 6 by means of the jaw 11 and screws 12. In assembling the blocks 5 and 6 upon the yoke 2, the same are first machined up, then fitted and dropped in, the yoke 2 having bottom inwardly extending shoulders 17 adapted to register with corresponding recesses 16 formed in the blocks 5 and 6, whereby the said blocks are registered and supported until suitable keys 15 can be driven into suitable slots 14 and 13 formed in said yoke, and gripper blocks, respectively. This construction is very plainly shown in Figures 2, 6 and 7. The gripper block 6 is movable relatively to the block 5, in order that the work 18 may be inserted between the jaws of said blocks, and this relative movement is effected by means of a nut 31 mounted in the forward end of the yoke 2 and adapted to receive and co-operate with an exterior threaded portion of the supporting trunnion 10, the latter having a hand wheel 32 mounted upon its forward end to effect its rotation and consequently the longitudinal movement of the block 6.

The attachment assembled as hereinbefore described, and holding the work 18, is adapted to co-operate with the well known collapsible tap 19 mounted upon a spindle 20 to which is secured a gear 21 adapted to mesh with a wide faced pinion 22 secured to a shaft 22', to which in turn is secured a bevel gear 23 co-operating with a bevel pinion 24 mounted upon a shaft 25 driven from any suitable source of power, not shown. The collapsible tap 19 is raised above the work 18 by means of the pivoted lever 26 suitably supported upon the tapping machine proper. The elements entering into these details of the operation form one unit of the complete machine, are well known to those skilled in the art, are of standard construction and adequately shown for the purpose, in Figure 1.

While the work 18 is being mounted in the attachment, it is desired to provide means whereby it will not be necessary to hold the weight thereof while tightening up the apparatus. I effect this result by means of a stop or support 27 provided with a bearing portion proper 28, plainly shown in Figure 6, said support 27 being pinned to a shaft 29 mounted in the table 1 and provided with an operating handle 30, whereby the member 27 can be removed from the flipping area of the yoke, gripper blocks and work, when it is desired to reverse the work in the manner now to be described in detail. Before this flipping or turning over of the attachment can take place, it is necessary to stagger the tooth-like members 3 and 4 so that they may pass each other. This is effected in the fol-

lowing manner: Pivoted to the forward end 65 of the table 1 is a link 33, to the outer end of which is pivoted a handle 34 having an upwardly curved portion 34', and secured thereto adjacently said portion 34' a downwardly curved strap portion 35, Figures 4 and 5. 70 Mounted upon a section 10' of the supporting trunnion 10 between two hub members 10' 75 is a yoke 36 having outer bead-like members 37 journaled in suitable holes formed in the strap 35 and the portion 34' of the handle 34. It is evident that the actuation of the handle 34 from the position shown in Figure 3 to that shown in Figure 2 will effect the movement of the trunnion 10 and the handle 32 and consequently of the yoke 80 2 and the teeth 4 to the position shown in Figure 2. It is further evident that then the rotation of the handle 32 will effect the turning of the yoke, gripper blocks and work, whereby the other end of the coupling 85 can be tapped, when the yoke has been locked again. This is effected by actuating the handle 34 to bring the several parts into the position shown in Figure 3, the rearward end of the yoke 2 striking and stopping against 90 the face 38 of the table 1. In order that the edges of the tooth-like members 3 and 4 may not interfere, when the members 4 are moved relatively to the members 3, the corners 39 are beveled, as plainly shown in Figure 9, in 95 which figure the members are moved in the direction indicated by the arrow when the same are moved to tapping position. In order that the forward edges of the teeth 4 may not interfere with the table 1, when the attachment is rotated, said teeth are beveled, as plainly indicated in Figure 8, by the ordinal 40.

In addition to the detail improvements hereinbefore described, hereinafter claimed, 105 and shown in the accompanying drawings, the invention provides means for rotating the work and its support in the table, when it is desired to tap the other end of the coupling, instead of removing this usually heavy 110 apparatus from the table by hand, turning it, and replacing it in the table.

What I claim is:

1. In attachments for tapping machines and the like, the combination of a table; a 115 yoke rotatably mounted therein, said table and yoke being formed respectively with co-operative members adapted to secure the yoke in the table; means for moving said yoke so that said members may be free one 120 from the other; means for effecting the rotation of the yoke; and gripper blocks mounted in the yoke.

2. In attachments for tapping machines and the like, the combination of a table; a 125 yoke rotatably mounted therein, said table and yoke being formed respectively with inwardly and outwardly extended members

adapted co-operatively to secure the yoke in the table; means for moving said yoke so that said respective members may be freed of engagement; means for effecting the rotation of the yoke; and gripper blocks mounted in the yoke.

3. In attachments for tapping machines and the like, the combination of a table; a yoke movable longitudinally thereof, said yoke being formed with shoulders along its inner lower edges; means for moving said yoke; and gripper blocks formed with recesses co-operating with said shoulders to support the blocks.

15 4. In attachments for tapping machines and the like, the combination of a table; relatively movable gripper blocks mounted thereon; a stop or support for the work; and means for moving said support into and 20 out of operative position beneath the work.

5. In attachments for tapping machines and the like, the combination of a table; a yoke movable longitudinally thereof; means for moving said yoke; a pair of relatively 25 movable gripper blocks mounted on said yoke; means for so moving said blocks; and a stop or support for the work pivotally mounted upon said table and adapted to be swung in under said blocks.

30 6. In attachments for tapping machines and the like, the combination of a table; a yoke mounted therein and movable relatively thereto, two series of co-operating tooth-like members formed respectively 35 upon said table and yoke, said members being arranged in staggered relation so that they can pass each other in a vertical plane, in one position of said yoke, and arranged to bear against each other to support the 40 yoke, in another position of the latter; a pair of trunnions; a pair of gripper blocks secured in the yoke; means for moving the yoke; and means for rotating the yoke and blocks upon said trunnions.

45 7. In attachments for tapping machines and the like, the combination of a table; a yoke longitudinally movable thereof; means for effecting such movements; two series of inwardly and outwardly extended blocks 50 formed upon said table and yoke, respectively, and adapted, in one position of said yoke, to be positioned one series above the other to support said yoke and, in another position of the latter, to be positioned so that one series can pass the other in a vertical plane; relatively movable gripper blocks mounted in said yoke; means for so 55 relatively moving said blocks; trunnions mounted in said table, said yoke being secured to said trunnions; and means for turning said trunnions.

8. In attachments for tapping machines and the like, the combination of a table; a yoke longitudinally movable thereof; means

for effecting such movements; two series of 65 inwardly and outwardly extended blocks formed upon said table and yoke, respectively, and adapted, in one position of said yoke, to be positioned one series above the other to support said yoke, and, in another 70 position of the latter, to be positioned so that one series can pass the other in a vertical plane; a pair of relatively movable gripper blocks; means for so relatively moving said blocks; means securing said blocks to 75 said yoke; a pair of trunnions mounted in said table, said yoke and one of said blocks being secured to said trunnions, respectively; and means for turning said trunnions.

80 9. In attachments for tapping machines and the like, the combination of a table; a yoke longitudinally movable thereof; means for effecting such movements; two series of inwardly and outwardly extended 85 tooth-like members formed upon said table and yoke, respectively, and adapted, in one position of said yoke, to be positioned one series above the other to support said yoke and, in another position of the latter, to be 90 positioned so that one series can pass the other in a vertical plane; a pair of relatively movable gripper blocks; means for so relatively moving said blocks, the yoke having inwardly extending shoulders, and the 95 blocks having co-operating recesses upon their outer faces to support the blocks; and trunnions mounted in said table, said yoke being secured to said trunnions, the means for effecting the relative movements of said 100 gripper blocks being adapted to turn said trunnions.

10. In attachments for tapping machines and the like, the combination of a table; a yoke supported thereon; relatively movable 105 gripper blocks mounted upon said yoke; means securing said blocks to said yoke; a trunnion secured to one of said gripper blocks and having an externally threaded portion; a nut secured in said yoke and 110 adapted to receive and cooperate with said trunnion; means for turning said trunnion; a second trunnion mounted in said table and secured to said yoke; means for releasing said yoke from its table support; and means secured to said first-mentioned 115 trunnion for actuating said yoke-releasing means.

11. In attachments for tapping machines and the like, the combination of a table; a 120 yoke longitudinally movable thereof; two series of inwardly and outwardly extended blocks formed upon said table and yoke, respectively, and adapted, in one position of said yoke, to be positioned one series 125 above the other to support said yoke; and, in another position of the latter, to be positioned so that one series can pass the other

in a vertical plane; a pair of relatively movable gripper blocks; means securing said blocks to said yoke; a trunnion secured to one of said gripper blocks and having an externally threaded portion; a nut secured in said yoke and adapted to receive and co-operate with said trunnion; means for turning said trunnion; a second trunnion mount-

ed in said table and secured to said yoke; and an operating lever pivoted at one end 10 upon said table and pivoted intermediately its ends to said first-mentioned trunnion.

Signed by me, this 13th day of March, 1920.

ALBERT J. BARBER.
